UNITED STATES PATENT OFFICE.

JOSEPH STICKLEY, OF MANSBRIDGE, SOUTH DAKOTA.

MATERIAL FOR FENCES.

SPECIFICATION forming part of Letters Patent No. 758,154, dated April 26, 1904.

Application filed July 18, 1903. Serial No. 166,173. (No model.)

To all whom it may concern:

Be it known that I, JOSEPH STICKLEY, a citizen of the United States, residing at Mansbridge, in the county of Charles Mix and State 5 of South Dakota, have invented a new and useful Material for Fences, of which the following is a specification.

This invention relates to metal fences of the class wherein movable barbs are employed at 10 suitable intervals, and has for its object to simplify and improve devices of this character and produce a fence material which is simple in construction, cheaply and easily manufactured, and which will possess great strength 15 and durability without increasing the expense or complication of parts.

The invention consists in certain novel features of construction, as hereinafter shown and described, and specified in the claim.

20 In the drawings illustrative of the invention, in which corresponding parts are denoted by like designating characters, Figure 1 is a perspective view of a section of fence constructed of the improved material. Fig. 2 is a side 25 view, and Fig. 3 is a transverse section, enlarged, of a portion of the improved material, illustrating its construction.

The improved material consists of spaced metal strips 10 11, preferably of flat elliptical shape in transverse section, as shown in 30 Fig. 3, and provided at intervals with registering transverse apertures formed in the thick central portion thereof, with studs 12 secured in the apertures, as by riveting.

35 Every alternate stud is provided with spacer members 13, and the remaining alternating studs are provided with spurs 14, mounted for rotation thereon. The spurs are each formed with a plurality of radiating sharp points

40 spaced apart, as shown, and of sufficient length to extend beyond the strips, as shown. The elliptical cross-sectional form of the strips provides for the firm supporting of the spur-wheels without binding thereof. The strips 45 thus constructed are attached to the posts, one of which is represented at 15, by staples 16 in the usual manner, and any number of the strips may be employed, and in practice the upper strips will be arranged with the

50 spurs and strips in a vertical position and one or more of the intermediate strips in reversed

position or with the spurs and strips horizontal, as shown in Fig. 1. Generally the upper strips will be placed with the spurs and strips vertical and the next lower strips reversed 55 and the remaining strips in the same position as the upper strips; but more of the strips may be arranged with the spurs and strips horizontal, if preferred.

The studs and the spacers and spurs supported by them may be disposed at any required distance apart, but will generally be arranged about one and one-half inches apart; but these distances may be varied, if required.

The material employed will be of iron or 65 steel of suitable "gage" and galvanized or otherwise coated to prevent corrosion.

The spurs 14 will be of metal of sufficient strength to resist the pressure to which they will be subjected, so that they will not bend 70 under the strains.

A fence constructed of this material possesses many advantages over the ordinary barb-wire construction in that while it repels the animals fully as effectually as the ordinary barb-wire it will not tear or rend them, as the spurs while prodding them when they come in contact with the points will not tear the flesh or hair, but will roll beneath the pressure and by constantly pricking the flesh 80 cause the animals to retreat without injury. The animals frequently approach fences at an angle thereto or brush along the wires, and when this takes place with the ordinary barb-wire construction the animals are frequently 85 severely torn and injured by the barbs.

With a fence constructed as above described, however, no such injury can take place, as the spurs will roll beneath the side or angular pressure and simply prick the animals 90 and cause them to quickly retreat without injury, as above noted. Moreover, the adjacent convexed faces of the strips fit closely to the spurs, so as to prevent undue lateral play thereof without interfering with the rotation 95 of the spurs and at the same time permit tilting of the spurs to prevent the same from becoming wedged between the strips, and thereby rendered non-rotatable.

Having thus described my invention, what 100 I claim is—

A fence-runner comprising a pair of com-

- paratively flat spaced strips having their adjacent faces convexed, a succession of fixed spacers carried by and located between the strips, a succession of rotatable spurs located
5 between the strips and alternating with the spacers, and fixed pivot-pins piercing the strips and the spurs with their opposite ends flush with the outer faces of the strips, each spur being loose to rotate upon its pin, and
10 the convexed faces of the strips fitting closely to the spurs to prevent undue lateral play

thereof and permitting tilting of the spurs, whereby the latter are prevented from becoming wedged between the strips and thereby rendered non-rotatable.

In testimony that I claim the foregoing as my own I have hereto affixed my signature in the presence of two witnesses.

JOSEPH STICKLEY.
